SHEDDING MECHANISM FOR CIRCULAR LOOMS

Joanny Jabouley, Spondon, near Derby, England,
assignor to Celanese Corporation of America,
a corporation of Delaware

Application January 12, 1934, Serial No. 706,319
In Great Britain January 24, 1933

10 Claims. (Cl. 139—16)

This invention relates to circular looms, and in particular to shedding mechanism therefor, the object of the invention being means to enable a variety of designs to be woven on circular looms.

5 A great difficulty in the control of warp threads for shedding purposes in circular looms is the necessity for effecting independent radial action of the healds or like devices by which the threads are controlled, for since passage of the warps as a cylinder coaxial with the loom enables the largest amount of fabric to be woven in relation to the diameter of the loom, the shedding movement must be effected by a radial or substantially radial movement of the warps out of the surface 10 of this cylinder, an arrangement which gives rise to considerable mechanical difficulties. Further, the warp density necessary for most textile fabrics requires a shedding control of the warp threads to be effected in several planes in order that the healds or like devices may be accommodated, and the mounting and operation of the devices in a plurality of banks offer many construction problems, especially owing to the circular arrangement of the machine.

20 25 The present invention enables these difficulties to be overcome by separating the mechanism bringing about the shedding movement of selected warp threads and the mechanism guiding the threads in such movement.

30 According to the present invention shedding is effected by means which press on the warps and tend to move them out of their normal path, locking means adapted to retain the warp threads in the normal path, and selector means adapted 35 to free some of the warps so as to permit them to move under the action of the pressing means. Thus, at each shedding point the warps may be engaged by a wheel projecting beyond the normal line of the warps while they remain in 40 engagement with the wheel so that the warp threads are pushed out of their normal line. Some distance from this wheel the warp threads pass through healds or like devices which are locked against movement so that notwithstanding 45 the movement of the warps under the action of the pressing wheel no effective movement takes place.

50 Selected healds are acted upon by suitable mechanism so as to free them from the locking devices, the healds thereupon moving under the pressure in the warp thread produced by the pressing wheel, so that any particular warp selected is separated from those still retained by the locked healds. In this way a shed is formed 55 which is either sufficient for the free passage of

the shuttle or, if desired, the extent of movement of the freed warps may be just sufficient to permit the shuttle to enter between the two sheets and thereafter force them apart.

Several forms of apparatus according to the 5 invention will now be described in greater detail with reference to the accompanying drawings, in which

Fig. 1 is a part sectional view of a shedding mechanism employing three banks of healds; 10

Fig. 2 is a view similar to Fig. 1 showing the release of healds in one of the banks;

Figs. 3 and 4 are plan views showing diagrammatically the spacing and mounting of the healds; 15

Fig. 5 is a view taken on the line 5—5 of Fig. 2;

Fig. 6 shows part of the periphery of the loom and shows the shedding of the warps for two consecutive shuttles;

Fig. 7 is a diagrammatic vertical section of the 20 periphery of the loom taken on the line 7—7 of the diagrammatic Fig. 6;

Fig. 8 is a similar view to Fig. 7 taken on the line 8—8 of Fig. 6;

Figs. 9, 10, and 11 show an alternative form 25 of selector mechanism for use with the healds shown in Fig. 1; and

Figs. 12, 13, and 14 show a further form of selecting mechanism.

Referring to Figs. 1, 3, and 4, extending between and secured in inner and outer rings 10, 11 are reed dents 12 and spacing pieces 13 arranged in alternation, the spacing pieces 13 extending upwardly beyond the face of the annular reed constituted by the dents 12. In the inner edges 35 14 of the inner set of spacing pieces 13 are square notches 15 to accommodate substantially square sectioned rings 16 at uniformly spaced vertical intervals. Similar rings 17 with a circular cross-section are secured in semi-circular 40 notches 18 in the inner edges of the outer series of spacing pieces 13.

Resting on the rings 16, 17 are three banks of healds 19 perforated mid-way between the rings 10, 11 with eyes 20 for the reception of warp 45 threads. The rings 17 as well as supporting the healds 19 form pivots for these healds, while the rings 16 engage square notches 16a in the lower edges of the healds and serve to lock the dents against longitudinal sliding. Rings 21 near the 50 upper ends of both series of spacing pieces 13 prevent accidental removal of the upper bank of healds 19.

The three banks of healds project outwardly beyond the outer series of spacing pieces 13 to 55

varying distances to form butts 22, 23, 24 lying below steps 25, 26, 27 in a cam-supporting ring 28 surrounding the healds. In the steps 25, 26, 27 can be secured cam plates 29 (see Figs. 2 and 5) having inclined ends, each cam plate being disposed somewhat in advance of each shuttle 30, as shown in Fig. 6.

The member 28 and the reed and heald supporting rings 10, 11 are arranged for relative angular movement in the loom; for instance, the shuttles 30 may rotate round the loom while the reed 12 and the warps remain stationary, or the warps may rotate while the shuttles are held stationary, as described in U. S. application Serial No. 655,560 filed 7th February, 1933. In either case, the cam plates 29 are arranged at a predetermined distance in advance of each shuttle so as to initiate the shedding movement in advance of each shuttle in turn.

20 As shown in Figs. 2 and 5, the action of the cam plates 29 is to depress slightly the butts 22, 23 or 24 at the outer ends of the healds opposite which the plates 29 are arranged, the depression of the outer ends of the healds causing the healds to pivot about the ring 17, so raising the inner ends of the healds and freeing them from the locking rings 16. Fig. 2 clearly shows the notch 16a at the middle bank of healds clear of its locking ring 16.

30 Also arranged at the forward end of each shuttle is a shedding wheel 31 mounted for free rotation on a support 32 and projecting inwardly beyond the normal line 33 followed by the warps from the spacing means 34 situated towards the top of the loom to the eyes 20 of the locked healds 19. All the warp threads are thus pressed by the wheel 31 and deflected inwardly above the level of the healds 19, as shown in Fig. 7. At each shuttle, however, one at least of the banks of healds 19 remains locked (there being no cam plate 29 provided on the member 28 in connection with those healds at that particular point), so that the warp threads 33x by passing through the locked healds remain undisplaced between the healds and a ring 35 disposed towards the bottom of the loom. The warp threads 33y passing through the eyes 20 of the bank of healds which has been freed by the cam plate 29 are, however, displaced inwardly between the healds and the ring 35, the freed healds 19 being carried inwardly with the warps 33y, as shown in Fig. 7. The warps 33x, 33y are thus separated into two sheets into which the nose 36 of the shuttle 30 can extend. The shedding wheels 31 are preferably fabric-covered, as described in U. S. application Serial No. 706,320 filed on even date herewith, to avoid slippage of the threads along the periphery of the wheels and also to minimize wear on the threads.

60 Continued passage of the shuttle 30 through the warps pushes the warp sheets apart sufficient for its passage between them, as shown in Figs. 6 and 8. At the rear end 37 of the shuttle 30 the separated warps return to a single sheet, the tension in the displaced warps 33y returning them to their normal line 33 and carrying the displaced healds 19 back to their normal position. By this time the butts on the outer ends of the healds are clear of the cam plate 29 and the inner ends of the healds are therefore free to drop into re-engagement with their locking ring 16. At the next shuttle further freeing of some of the healds 19 takes place by suitable cam disposition in accordance with the type of weave

desired, and a new shed is formed for the following shuttle.

While three banks of healds 19 have been shown, any other suitable number of banks may be employed, with a corresponding number of cam-steps in the member 28. For example, five banks of healds may be used for the weaving of 5 5-shaft satin. Further, instead of the member 28 and the shedding wheels 31 being disposed outside the warp circle, they may be arranged within 10 the circle.

Referring now to Figs. 9-11, the cams 29 are replaced by notched wheels 38 which lie over the butts 22, 23, 24 and project downwardly sufficiently to depress the butts in a manner similar 15 to the cams 29. Fig. 10 shows some of the butts 22 depressed by the periphery of the wheel 38, while other butts lying in the notches 39 remain undepressed.

Thus the wheels 38 make a selection of the 20 healds in any particular bank which are to be released for movement under the displacing action of the shedding wheels 31, and patterned shedding is effected in accordance with the 25 position of the notches 39.

Figs. 13 and 14 show a modified form of presser wheel to displace the warps above the healds 19 selected in the manner above described. This wheel 40 is formed with notches 41 in its periphery, the notches being deep enough to permit 30 the passage of threads without displacement of the threads under the action of the wheel. Threads falling against the periphery of the wheel 40 are displaced so that freed healds 19 are moved to one side, as shown in Fig. 14, for the 35 entry of the shuttle nose 36 between the two sheets of warps thus formed.

In order to prevent threads from slipping away from the periphery of the wheel 40 into the notches 41, small projections 42 are formed at the 40 sides of each notch, as shown in Fig. 13.

More or less complicated shedding can be obtained with this arrangement, depending on the size of the wheel 40 and the disposition of the notches 41.

What I claim and desire to secure by Letters Patent is:—

1. Circular loom shedding mechanism comprising means to press on the warps and deflect them from their normal path, healds controlling 50 the warps, locking means for said healds, and selector means adapted to free some of the healds so as to permit the warps controlled by such healds to move under the action of the pressing means.

2. Circular loom shedding mechanism comprising means to press on the warps and deflect them from their normal path, a plurality of banks of healds controlling the warps, locking means for said healds, and selector means adapted to free healds in any predetermined bank so as to permit the warps controlled by such healds to move under the action of the pressing means.

3. Circular loom shedding mechanism according to claim 1 comprising as selector means a 65 notched wheel disposed so as to engage a series of healds, healds falling into the notches of the wheel remaining locked and the others being freed by the wheel.

4. Circular loom shedding mechanism comprising a circular reed, spacing pieces alternating with the ends of the reed dents and projecting from one face of the reed, healds slidably mounted between pairs of the spacing pieces, locking means to prevent sliding movement of 70 75

the healds, means to free selected healds from the locking means, and means to press on the warps controlled by the healds and to deflect from their normal path those warps the healds of which have been freed.

5. Circular loom shedding mechanism according to claim 4 wherein the healds are arranged in several banks, the healds in the different banks projecting to form butts, and wherein the 10 heald-freeing means comprises cams adapted to engage the butts of healds in selected banks.

6. Circular loom shedding mechanism according to claim 4 wherein the healds project to form butts and wherein the heald-freeing means comprises a notched wheel disposed so as to engage 15 said butts, healds falling into the notches of the wheel remaining locked and the others being freed by the wheel.

7. Circular loom shedding mechanism comprising a notched wheel adapted to press on the warps and to deflect warps not falling into the notches, healds controlling the warps, locking means for said healds, and selector means adapted to free some of the healds from the locking 20 means so that warps both from the locking means and deflected by the notched wheel are separated from the remaining warps.

8. Circular loom shedding mechanism according to claim 7 wherein the notched wheel is provided with projections at the sides of each notch to prevent threads engaged by the periphery of the wheel from slipping into the notches.

9. Circular loom shedding mechanism comprising a circular reed, spacing pieces alternating with the ends of the reed dents and projecting from one face of the reed, healds slidably mounted edge uppermost between pairs of the 10 spacing pieces, said healds being perforated to receive warp threads, each heald thereby being adapted to effect a sliding movement between the spacing pieces to deflect from its normal path that warp thread controlled by the heald, and 15 means to effect a selection among the healds so as to bring about a deflection of the corresponding warp threads.

10. Circular loom shedding mechanism according to claim 9, comprising a ring supported 20 by the spacing pieces, the healds resting on said ring, and notches in the lower edges of the healds adapted to engage said ring, said engagement of the notches with the ring normally locking the healds against sliding movement between 25 the spacing pieces.

JOANNY JABOULEY.
